UNITED STATES PATENT OFFICE.

MORGAN A. GREEN, OF RUPERT, IDAHO.

BEET-TOPPER.

1,321,737.

Specification of Letters Patent. Patented Nov. 11, 1919.

Application filed April 24, 1918. Serial No. 230,524.

To all whom it may concern:

Be it known that I, MORGAN A. GREEN, a citizen of the United States, residing at Rupert, in the county of Minidoka and State 5 of Idaho, have invented new and useful Improvements in Beet-Toppers, of which the following is a specification.

This invention relates to new and useful improvements in beet harvester and the 10 principal object of the invention is to provide improved means for cutting off the tops of the beets before being harvested.

The present invention is an improvement over that described in the application filed 15 by me on October 29th, 1917, Serial No. 199,047.

Another object of the invention is to provide a device of this character which is simple and durable in construction, reliable 20 and efficient in operation and one which can be manufactured and placed upon the market at a minimum cost.

The invention also consists in certain other features of construction and in the 25 combination and arrangement of the several parts, to be hereinafter fully described, illustrated in the accompanying drawings and specifically pointed out in the appended claims.

30 In describing my invention in detail, reference will be had to the accompanying drawings wherein like characters denote like or corresponding parts throughout the several views, and in which:—

35 Figure 1 is a side view of a beet harvester to which my invention is applied.

Fig. 2 is a plan view with parts omitted.

Fig. 3 is a plan view with parts in section of the topper attachment.

40 Fig. 4 is a side view with parts in section of the attachment.

As shown in these views the machine comprises a frame A provided with a front truck B and having its rear end supported 45 by the wheels 15 which are mounted on the axle 16.

As before stated the present improvement relates to the topping means for topping the beets before they are dug by the plows and 50 such means consist of the frame 3 formed of angle or like bars. These bars are provided with cylindrical portions 3' which engage circular portions 2 of the frame A which support the shaft 16. The parts 3' and 2 are so arranged that the frame 3 may be raised and lowered with the part 2 acting

as a pivot therefor. As will be seen the bars forming the frame 3 are spaced apart both horizontally and vertically and at the front ends the lower bars support the shafts 60 4 which project downwardly as shown. These shafts carry the rollers 5 for the endless belt 6, preferably composed of metal links to which the cutting teeth 7 are secured at the lower edge thereof. I prefer to make 65 the rollers 5 of concave shape so as to firmly hold the belt 6 thereon. In the operative position of the topper the axles 4 are inclined so that the cutting teeth 7 on the front stretch of the belt project downwardly 70 as shown. One of the shafts 4 is driven by means of the beveled gear 8 meshing with the similar gear 9 on the shaft 10 which is driven from the axle 16 by means of the gears 11. The other shaft 4 is adjustably 75 mounted in a part of the frame which is slotted to permit said adjustment.

12 indicates a roller having its ends carried by the adjustable posts 13 so that said roller may be adjusted vertically and one 80 of said posts slidingly engages the gear 13' meshing with the gear 13^x carried by an extension of the shaft 10. Said post also carries the gear 14 which meshes with the gear 14' carried by the roller. 85

22 indicates a flattening roller carried by the post 23 at the front of the frame 3. 24 are uprights secured to the front end of the frame 3 and having the cross piece 25 at the upper ends. 90

When necessary I may provide counter-balancing means for the frame 3 so that the parts carried by said frame will move with the least possible effort.

It will be seen that as the harvester moves 95 forward the roller 22 will flatten out the beet tops so that the roller 12, which is a gaging roller for regulating the position of the cutting teeth, will not be caused to rise by the beet tops. As before stated the roller 100 12 is adjustable so that the cutting teeth may be made to engage the tops at any desired distance from the body of the beet. It will also be seen that when the plows are lifted upwardly the topper means will also 105 be carried upwardly out of operative position.

It is thought from the foregoing description that the advantages and novel features of my invention will be readily apparent. 110

I desire it to be understood that I may make such changes in the construction and

in the combination and arrangement of the several parts, provided that such changes fall within the scope of the appended claims.

What I claim is:—

- 5 1. In combination with a beet harvester, a topper attachment consisting of an elongated frame having one end pivoted to the drive shaft of the harvester, an adjustable roller at the other end of said frame, a pair 20 of vertically disposed rollers on the frame adjacent said first mentioned roller, cutting means carried by said rollers, gears connected with one of the vertical rollers and with the adjustable roller and a shaft carried by the frame and having gears thereon 25 engaging the before mentioned gears, said shaft being connected with the drive shaft of the harvester.
- 10 15

2. In combination with a beet harvester,

Copies of this patent may be obtained for five cents each, by addressing the "Commissioner of Patents, Washington, D. C."

a topper attachment consisting of an elongated frame having one end pivoted to the drive shaft of the harvester, an adjustable roller at the other end of said frame, a pair 20 of vertically disposed rollers on the frame adjacent said first mentioned roller, cutting means carried by said rollers, gears connected with one of the vertical rollers and with the adjustable roller and a shaft carried by the frame and having gears thereon 25 engaging the before mentioned gears, said shaft being connected with the drive shaft of the harvester.

In testimony whereof I affix my signature. 30

MORGAN A. GREEN.
